UNITED STATES PATENT OFFICE.

WILLIAM YAEGER, OF NEW YORK, N. Y., ASSIGNOR TO STRAUSS & CO., INC., OF NEW YORK, N. Y.

DESIGN FOR A TICKET-BOOTH.

45,442.

Specification for Design.

Patented Mar. 17, 1914.

Application filed November 21, 1913. Serial No. 802,318. Term of patent 7 years.

To all whom it may concern:

Be it known that I, WILLIAM YAEGER, a citizen of the United States, residing in the city of New York, borough of Manhattan, in the county and State of New York, have invented a new, original, and ornamental Design for a Ticket-Booth, of which the following is a specification, reference being had to the accompanying drawings, forming part thereof.

The figure is a perspective view of a ticket booth showing my new design.

I claim:

The ornamental design for a ticket booth as shown.

WILLIAM YAEGER.
